ULTRAHIGH-FREQUENCY ELECTRON
DISCHARGE TUBE APPARATUSMarvin Chodorow, Kew Gardens, N. Y., assignor
to The Sperry Corporation, a corporation of
Delaware

Application January 29, 1947, Serial No. 725,106

6 Claims. (Cl. 315—5)

1

The present invention relates to the art of ultra-high-frequency apparatus, including electron discharge tubes of the velocity modulation type, and utilizing cavity resonators operating at frequencies of the order of 1,000 to 30,000 megacycles per second. More particularly, the invention relates to arrangements for coupling said tubes to other high-frequency apparatus and for varying the operating frequency of the tubes.

Cavity resonators, as employed in high-frequency electron discharge tubes or other high-frequency apparatus, have been made in a variety of symmetrical shapes and with various types of coupling devices for introducing high-frequency energy into or extracting high-frequency energy from the resonators. The operating frequencies of such resonators have been variably controlled by diverse types of tuners, of which one known form comprises a conductive rod member mounted to be adjustably positionable within the resonator so as to alter the value of frequency-controlling parameters thereof and to change the frequency of operation of the tube accordingly.

However, the tuners and couplings heretofore employed have been selected in the light of mutually independent and, generally, incompatible design and operational requirements. Thus, in the prior art, conductive rod tuners have been introduced into regions of intense electric-field or intense magnetic-field components of an excited cavity resonator, thereby causing alteration of the equivalent capacitance or the equivalent inductance of the resonator. The former method is generally referred to as capacitive tuning of the tube while the latter is known as inductive tuning.

Where such capacitive or inductive tuning means are embodied in conventional symmetrically shaped cavity resonators having conventional input or output coupling loops, it has been observed that such a combination of tuner and coupling is seriously limited as to operable tuning range because of the difficulties experienced in orienting the conductive rod so as to lie entirely in either the electric-field portion or the magnetic-field portion of the electromagnetic field within the resonator. It has been found, for example, that insertion of the tuning rod beyond a certain limited amount fails to provide frequency alteration corresponding to the increased insertion, due to the fact that the rod then lies in a region occupied by both electric- and magnetic-field components of substan-

2

tially equal magnitude, thus producing practically no net tuning effect. As a result of such tuning-range limitations, the utility of the cavity resonator apparatus of the prior art has been seriously restricted.

A principal object therefore, of the present invention is to provide generally improved tunable cavity resonator apparatus wherein the above-described difficulties are avoided.

10 Another object is to provide a high-frequency electron discharge tube of the velocity-modulation type having an improved cavity resonator embodying novel arrangements of tuning and coupling means mutually cooperable to produce a substantially increased range of tuning for the tube.

In accordance with the present invention, broad-band tuning is accomplished in an ultra-high-frequency electron discharge tube device 20 by means of a novel type of cavity resonator having an axially slotted wall portion and wherein in a waveguide coupling arrangement and a conductive tuning member are provided in substantially diametrically opposed portions of the resonator. Increased range of tuning has been found to result from the fact that the asymmetry of the resonator structure produced by this novel arrangement enables the positioning of the tuning member substantially exclusively in the magnetic-field portion of the resonator field 25 thereby minimizing undesired capacitance effects. Furthermore, it has been discovered that variations of the effective inductance value of the resonator portion occupied by the tuning member, in accordance with the present invention, produces a relatively greater change in the total effective inductance of the resonator than is produced by a corresponding change in conventional resonators.

30 Accordingly, it is another object of the present invention to provide an improved high-frequency apparatus having increased tuning range provided by an asymmetrical resonator arrangement including an axially slotted cavity resonator having a wave guide coupling at the slotted portion of the resonator and a conductive tuning member in a diametrically opposed portion of the resonator.

35 Still another object of the invention is to provide a cavity resonator device of increased tuning range comprising an axially slotted cavity resonator having a wave guide section coupled to the slotted portion thereof and a conductive tuning member adjustably disposed within 40 a portion of the resonator diametrically opposed

from said slotted portion and translatable chordwise therein, whereby, for a certain mode of excitation of said resonator, adjustment of the position of the tuning member produces substantially pure inductive tuning of the resonator.

A feature of the present invention lies in the provision of an ultra-high-frequency apparatus comprising a cylindrical cavity resonator having an axially slotted wall portion, a wave guide section coupled to said resonator at the slotted portion thereof, and a tuning rod adjustably positionable within the resonator in a region diametrically opposed from the slotted wall portion.

Another feature of the present invention is the provision of a novel reflex oscillator of the klystron type having a waveguide coupling arrangement and a conductive rod tuner cooperable with said coupling arrangement to produce an increased range of tunability for said oscillator.

The invention in another of its aspects relates to novel features of the instrumentalities described herein for achieving the principal objects of the invention and to novel principles employed in those instrumentalities, whether or not these features and principles are used for the said principal objects or in the said field.

A further object of the invention is to provide improved apparatus and instrumentalities embodying novel features and principles, adapted for use in realizing the above objects and also adapted for use in other fields.

The above and other objects and advantages of the invention will be apparent from the particular description thereof made in connection with the accompanying drawing in which:

Fig. 1 is a plan view, partly broken away, of a conventional type of coaxial cylindrical cavity resonator useful in describing certain features of the present invention.

Fig. 2 is a schematic showing of an equivalent lumped-constant circuit of the cavity resonator shown in Fig. 1.

Fig. 3 is a transverse, cross-sectional view of a cavity resonator embodying certain features of the present invention.

Fig. 4 is an elevational view, partly in longitudinal section, of an ultra-high-frequency velocity-modulation reflex oscillator embodying a resonator of the type shown in Fig. 3.

Fig. 5 is a cross-sectional view of the oscillator of Fig. 4 taken along the line 5—5 thereof, and

Fig. 6 is a fragmentary cross-sectional view taken along the line 6—6 of Fig. 4.

Referring to Fig. 1, a conventional type of ultra-high frequency cavity resonator is shown having a conductive cylindrical wall 11, a coaxially disposed conductive inner rod 13 and end walls 15 and 17 enclosing the cylinder at top and bottom, respectively. Rod 13 is connected at one end to one end wall, such as 15 and is adjacent but spaced from the other end wall. As is well-known, the enclosure thus formed defines a space resonant system, which, for a given mode of oscillation, is resonant at a frequency, f , defined by

$$f = \frac{1}{2\pi\sqrt{LC}} \quad (I)$$

where L represents the equivalent inductance and C the equivalent capacitance of the resonator.

The resonator of Fig. 1 may be represented by a lumped-constant network which, as illustrated in Fig. 2, comprises inductors 19, 21 connected in parallel to each other and to a capacitor 23. The

lumped inductances of inductors 19, 21 respectively represent the equivalent inductances L_1 , L_2 of the respective half-portions 25, 27 of the resonator (Fig. 1) to the left and right of a diametral plane 29 drawn through the resonator, while the lumped capacitance of capacitor 23 represents the equivalent capacitance of the resonator.

The joint equivalent inductance L of the resonator is approximately given by the well-known relation

$$L = \frac{L_1 \cdot L_2}{L_1 + L_2} \quad (II)$$

Since the resonator is symmetrical about the plane 29, the equivalent inductance L_1 is equal to the equivalent inductance L_2 , and for this condition $L = \frac{1}{2} L_1 = \frac{1}{2} L_2$.

For a fixed value of the equivalent capacitance C , the resonant frequency f of the resonator depends on the value of the joint equivalent inductance L . In the conventional cavity resonator case disclosed, the equivalent inductances L_1 , and L_2 of half-portions 25, 27, respectively contribute equally to the joint value of the equivalent inductance L . A limited degree of variation of the inductances of either of the half-portions 25, 27 is provided, in the prior art, by inserting a conductive rod 31, or similar conductive member, radially into the resonator. The variation of inductance thus produced gives rise to a corresponding variation of the resonant frequency of the resonator. As noted hereinabove, such frequency variations have proved to be seriously limited as to workable range.

By the present invention, a substantial increase in the range of frequencies over which such a resonator may be tuned is provided by the use of the cavity resonator illustrated in Fig. 3. Here, the resonator is generally similar to the resonator 11, 13 of Fig. 1, with the exception that a portion of the wall 33 is cut away as by a plane passed parallel to the axis of the cylinder, and at a predetermined distance therefrom, to form a longitudinally extending slot 35 the width X of which depends on the said predetermined distance from the axis at which the slot is formed.

The equivalent inductance of the region adjacent the slotted wall section of resonator is larger than that of the unslotted section; that is, the region remote from the slot, by an amount proportional to the width X of the slot 35. Thus, since the slot 35 may be made of any desired width consistent with mechanical design considerations, the inductance L_2 may be made correspondingly large. For a slot width X of order of magnitude approximately one-third the diameter of the cylinder, or greater, the total equivalent inductance L of the slotted resonator is largely determined by the inductance L_1 of the unslotted portion. It will thus be seen that under such conditions variation of the inductance L_1 of the unslotted portion produced, for example, by variation in position therein of a conductive tuning rod 37, gives rise to a greater proportionate effect on the total equivalent inductance L , resulting in a correspondingly greater effect on the resonant frequency of the resonator.

An alternative way of considering the increased tuning range of a cavity resonator having a slotted side wall portion is to regard the resonator as a coaxial line section terminated in a capacitance. If the characteristic impedance of the coaxial line section be Z_0 , the effect of introducing a conductive rod into the space between the inner and outer conductors of the line is to

decrease the value of Z_0 thereby changing the resonant frequency of the cavity resonator. Cutting a slot into the wall of the outer conductor effectively transforms the line section into an eccentric transmission line of eccentricity ϵ and simultaneously changes the characteristic impedance to some other value Z_0' . From the theory of eccentric transmission lines, it may be deduced that the rate of change of characteristic impedance with respect to eccentricity,

$$\frac{dZ_0}{d\epsilon}$$

increases as the value of the eccentricity is increased. Thus, a given displacement of the outer conductor of the line "off" concentricity will have a greater effect on the value of the characteristic impedance, the greater the value of the eccentricity. Therefore, it follows that the tuning range of a plunger employed in such an apparatus will be increased if the line is made initially eccentric as by providing a slot in the side wall of the outer conductor.

While alternative explanations of the principles on which the novel features of the invention may be based have been proffered, it is to be understood that the invention is not to be conditioned or limited upon either or both of these explanations, these having been given merely to clarify the description of the invention.

Still greater broad-banding is provided by the present invention by introducing the rod 37 chordwise into the resonator, as shown, thereby permitting a greater volume of resonator to be occupied by the rod, than is possible by the prior art radial motion.

Figs. 4 to 6 show an adaptation of my broad-band tunable cavity resonator to an ultra-high-frequency electron discharge tube which, in the illustrated embodiment, is of the electron velocity-modulation type, known in the art as a reflex klystron.

It will be understood that the invention is not limited to application in reflex klystrons, but may be utilized in all types of high-frequency apparatus wherein broad-band tuning is desired.

As shown, tube 39 comprises a cavity resonator 41 formed by a substantially cylindrical conductive wall 43 and a pair of centrally apertured conductive end walls 45, 47. It will be noted that resonator 41 is preferably formed with relatively thick metallic walls for good heat-radiating characteristics, thereby minimizing undesirable frequency drifting due to alteration of the resonator dimensions caused by fluctuations in operating or ambient temperature conditions.

It will be noted that, while the walls 43, 45 and 47 are herein disclosed as being formed from a solid block of conductive material suitably machined to define the cavity resonator 41, this disclosure is merely illustrative of one manner of fabrication. Such a resonator may, if desired, be formed in diverse other ways, such as by stacking and interconnecting suitably-formed sheets or laminations of metal which, in assembly, define substantially the same resonator configuration as disclosed.

Supported in the central aperture of end wall 45 and projecting coaxially within resonator 41 is a tubular member 49 having aligned parallel grid structures 51, 53 at its inner and outer ends respectively. The aperture of end wall 47 may be provided with a similar grid structure 55 which, together with grids 51, 53 and tube 49 define a path for a beam of electrons supplied by a cathode assembly 57 of any suitable conventional

type. Cathode assembly 57 may include a focusing control or modulating electrodes, as desired.

For reflecting the beam of electrons, a reflector electrode 59 is rigidly sealed into the tube 39 by means of a structural arrangement which is particularly adapted to minimize microphonics. This arrangement comprises a conductive tubular member 61, vacuum-sealed to the outer surface of end wall 47 and in coaxial alignment with the central aperture therein. The outer end of tubular member 61 is flared as at 63 to provide a shoulder at which a correspondingly flared outer periphery of a concavely-dished cap 65 may be sealed to form an air-tight, mechanically rigid joint.

Cap 65 is centrally apertured for receiving an insulating support 67 which is formed with a downwardly extending hollow cylindrical part 69 and a bush 71. The support may be of glass or other electrical insulating material suitable for bonding to metal. Bush 71 is preferably vacuum-sealed into the aperture of cap 65 with the free end of the cylindrical part 69 bonded in butt fashion to reflector electrode 59. Lead-in wire 73 for providing electrical connection between reflector electrode 59 and an external source of a potential, not shown, is suitably molded in the insulating support 67 and conductively connected to reflector electrode 59.

As thus far described, the reflex klystron tube 39 is of substantially conventional design and operation. The electrons from the cathode 57 are accelerated to form a beam by a suitable voltage impressed between grid 53 and cathode 57. This beam initially traverses the gap between resonator grids 51, 55 and is thereafter returned into the resonator 41 by reflector electrode 59 so as to excite and maintain an oscillatory electromagnetic field therein. Accepted theories of this action based on velocity modulation principles are explained fully in Fig. 2 of U. S. Patent No. 2,250,511, issued July 29, 1941, to Russell H. Varian and William W. Hansen, to which reference is made for further details.

Wide-band inductive tuning of tube 39 is accomplished by means of a movable plunger which may be in the form of a conductive rod 75 mounted for chordwise projection into the interior of resonator 41. As shown, rod 75 is preferably cylindrical in shape and of cross-sectional dimension practically to fill the space between end walls 45 and 47 and tubular member 49 and the adjacent portion of cylindrical wall 43. Also, the inner end of rod 75 is preferably rounded to form a hemispherical tip to reduce undesired capacitance effects.

Variable adjustment of rod 75 from the outside tube 39 is afforded through the use of a vacuum-tight bellows arrangement to be described.

Fig. 5 shows the structure of one type of bellows arrangement which may conveniently be used to adjust the position of conductive rod 75. As disclosed, the arrangement is fixedly attached to the outside of the cylindrical wall 43 of resonator 41 at a chordwise extending opening 77 formed in the wall. Opening 77 communicates with the interior of the resonator and is formed with a pair of coaxially disposed, relatively small-bore and large-bore portions 79, 81, respectively, through which rod 75 extends.

A sleeve 83 having an axial bore of substantially the same diameter as that of the small-bore portion 79 and a radial flange 85 at the inner end, is rigidly seated in the large-bore por-

tion 81 of the opening with the flange 85 brazed or otherwise conductively connected to the resonator wall 43. A second sleeve 87, having an annular shoulder 89 formed at its inner end and a radially extending flange 91 at the other end, is tightly fitted and conductively secured in the large-bore portion 81 of opening 77, with sleeve 83 telescopically received within sleeve 87. The outer diameter of sleeve 83 and the diameter of the bore of sleeve 87 are so selected that, when assembled, the adjacent lateral surfaces of the sleeves are slightly spaced, forming a cylindrical slot or space 93 extending coaxially between sleeves 83 and 87. The bore of sleeve 87 is slightly longer than sleeve 83 so as to provide a radial slot or space 95 which, as shown, connects with the cylindrical slot 93 to form a continuous inverted U-shaped slot in cross-section, the overall length of which is chosen to be substantially one-quarter wavelength at the average operating frequency of the tube.

As is well-known in the art, a slot of the inverted U-shaped type hereinabove described forms a folded short-circuited quarter-wavelength transmission line section which provides a very low impedance, amounting practically to a short circuit for ultra-high-frequency energy of frequency corresponding to the average operating frequency of the device, as seen looking along opening 77 from the interior of the resonator 41 outwardly. Accordingly, it will be seen that practically no electromagnetic energy of this frequency can leak out of or be radiated from the interior of the resonator through the opening 77. Other suitable means may be provided for the same radiation-inhibiting or wave-trap purpose.

The radially extending flange 91 of sleeve 87 provides an anchor plate for mounting one end of a flexible bellows 97 in vacuum-tight manner, the other end of which is fixedly secured and sealed to a radially extending flange 99 of an internally threaded travelling nut 101 which is adjustable toward or away from flange 91 by rotation of a rotatable screw shaft 103 in one sense or the other. Rod 75 may be affixed to the nut 101 in any suitable manner or may be integrally formed with nut 101 to be movable therewith, and thus to be adjustably translatable within the resonator 41. As shown, the outer end of shaft 103 is turned smooth so as to extend through and be rotatable in a bearing 105 provided in a metallic cylindrical dust-proof cover 113 which, in turn, is preferably detachably connected to flange 91, as by means of machine screws 115. Shaft 103 is secured against inadvertent translatory movement by means of a snap-washer 106 fitted into an annular groove in the shaft 103 and a similar washer, not shown, at the other end of bearing 105. A knurled knob 107 may be provided to facilitate manual operation of the screw shaft 103. Also, a pointer 109 and scale 111 may be provided if visual indication of the position of the rod 75 and hence of the resonator frequency is desired.

For coupling tube 39 to a load, which, in the illustrative embodiment is represented as a wave guide section 117, a slot 119 is formed in a side wall portion of the resonator 41 on the side substantially diametrically opposite the tube 49. Such a slot may be formed by milling or otherwise machining a groove 121, Fig. 4, into the wall 43 of the resonator to a depth corresponding to a desired width of slot. It will be understood that, where the resonator is built up by stacking per-

formed metallic laminations, as hereinabove where the resonator is built up by stacking preliminarily forming such laminations so as to provide, in assembly, such a groove and slot.

- 5 A section of oval wave guide 123, dimensioned above cut-off at the mean operating frequency and having spaced parallel top and bottom walls 125, 127 and substantially cylindrical side walls 129, 131, Fig. 6, is mounted in the groove 121 at the slot 119. One end of the wave guide 123 is open and communicates with the interior of the resonator 41 through slot 119. As shown in Fig. 6, the transverse dimensions a , b of wave guide 123 are preferably substantially greater than the dimensions of slot 119. The other end of the wave guide is vacuum sealed as at 133 by means of any suitable dielectric material which is readily transparent to high-frequency electromagnetic waves.
- 10 Wave guide section 123 is adapted to be telescopically received within the wave guide 117, as shown, and secured thereto by means of machine screws 135 threaded into suitable openings in a conventional choke flange coupling 137 having one portion fixed to resonator 43 and a second cooperating portion fixed to wave guide 117. It will be understood that any suitable wave trap 139 or radiation-inhibiting coupling arrangement between the wave guide sections 117 and 121 may be utilized as desired.

15 It has been found that the wave guide coupling herein described affords a wide selection of degrees of coupling between the electromagnetic energy within the cavity resonator of tube 39 and an external load, the factors determining the degree of coupling being the width x of the slot 119, the length l of the wave guide 123 extending into wave guide 117 and the transverse dimensions a , b of wave guide section 123. It has also been found that, by selection of suitable values for these factors, substantially any desired degree of coupling may be obtained.

20 In one embodiment, for operation in the band of frequencies ranging between 4800 megacycles per second and 5200 megacycles per second, satisfactory operation into a load in the form of conventional 1-inch by 2-inch wave guide is obtained by means of a wave guide section 121 having the following values:

$$\begin{aligned} x &= \frac{1}{2} \text{ inch} \\ 1 &= 1\frac{3}{8} \text{ inch} \\ a &= 1.8 \text{ inch} \\ b &= 0.5 \text{ inch} \end{aligned}$$

25 It will, of course, be understood that where other degrees of coupling are desired, or where operation at a different range of frequency values is desired, other suitable values for these factors may be selected.

30 It has also been found that in the above-described embodiment, utilizing the values indicated, a range of variation of operating frequency of 400-500 megacycles per second is obtainable, which represents a considerable increase over that afforded in prior-known types of apparatus.

35 Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

40 What is claimed is:

- 45 1. High-frequency apparatus comprising an electron discharge device having a cylindrical

cavity resonator as a frequency-determining element thereof, said resonator having a slotted portion, the region of said cavity resonator adjacent the slotted portion thereof having a substantially larger effective inductance compared to the effective inductance of said cavity resonator remote from said slotted portion to render said cavity resonator asymmetrical, said resonator being suitable for supporting an electromagnetic field therein, a conductive tuning member projecting into said resonator through a cylindrical wall portion thereof substantially diametrically opposite said slotted portion of said resonator, said tuning member being movable substantially entirely within a region of said resonator suitable for containing magnetic field components of said electromagnetic field, and means coupled to said tuning member for varying the amount of projection of said tuning member within said cavity resonator so as to vary the effective volume thereof, thereby producing broad-band variation of the operating frequency of said device.

2. Ultra-high-frequency electron discharge tube apparatus comprising means for forming and projecting a beam of electrons along a predetermined path, conducting walls defining a hollow cavity resonator surrounding the path of said beam, said resonator having a slotted wall portion, a first portion of said resonator having a larger effective reactance value than a further portion of said resonator, means in the path of said beam for reversing and re-projecting said beam through said resonator, whereby ultra-high-frequency energy is generated within said resonator, and tuning means in a further portion of said resonator for varying the effective reactance value of said further portion, said tuning means including a conductive member adjustably disposable in said further portion, whereby the difference in the effective reactances of said portions produces upon adjustment of said conductive member a relatively large variation of the total effective reactance of said resonator.

3. High frequency apparatus comprising conducting walls defining a cavity resonator, said cavity resonator having an opening in a wall portion thereof, a first section of hollow wave guide sealed at one end thereof at said wall portion about said opening, a gaseous-tight seal at the other end of said wave guide whereby said first section of hollow wave guide together with said conducting walls defining said cavity resonator comprise a unitary gaseous-tight body, and a second section of hollow wave guide receiving said other end of said first section of wave guide, said first section of wave guide projecting a predetermined electrical length into said second section of wave guide and having predetermined cross-sectional dimensions to effect a desired impedance discontinuity so that a desired coupling sensitiveness for energy coupled from said resonator to said second wave guide is afforded.

4. A tunable cavity resonator comprising a conductive substantially cylindrical wall means having a slot, spaced conductive end wall means disposed at the ends of said cylindrical wall means, an electron-permeable gap centrally disposed with respect to said cylindrical wall means, the effective inductance of a first region of said cavity resonator adjacent said slot being relatively large compared to the effective inductance of a second region of said cavity resonator, and a conductive member having chord-

wise translation within said cavity resonator for varying the effective volume thereof, the axis of said conductive member being displaced from said electron-permeable gap, said conductive

- 5 member being adjustably disposable within said second region and being further substantially diametrically opposite said slot to produce a variation of the effective inductance of said second region, whereby the operating frequency of said resonator may be varied over a relatively wide range.
5. A tunable cavity resonator comprising a conducting body having substantially toroidal inner wall portions, said cavity resonator being inductively asymmetrical about its axis of revolution, one region of said resonator having a relatively large effective inductance compared to a second region thereof, said resonator having an aperture in the wall thereof adjacent said one region, and means for varying the effective volume of said cavity resonator, said last-named means comprising an adjustable conductive element confined to said second region within said cavity resonator beyond said axis of revolution and remote from said aperture for producing a variation of the effective inductance of said second region, whereby the operating frequency of said cavity resonator may be varied over a relatively wide range.
- 15 6. Ultra-high frequency electron discharge tube apparatus comprising a cylindrical cavity resonator having hollow axial reentrant portions defining an electron permeable gap, said cavity resonator having an aperture through the cylindrical side wall thereof, waveguide output means including a gas-tight seal coupled to said cavity resonator for receiving ultra-high-frequency energy through the aperture in said side wall, and a conductive tuning plunger projecting into said cavity resonator through the cylindrical side wall at a region separate from said aperture to vary the volume of said cavity resonator, said tuning plunger being movable along a chord of said cavity resonator lying
- 20 25 30 35 40 45 50 55 60 65 70 75

between said gap and said side wall of said cavity resonator whereby the plunger extends into said cavity resonator for a distance greater than the radial distance between said gap and said side wall.
